UNITED STATES PATENT OFFICE.

WILEY EDMONSON, OF BICKNELL, INDIANA.

SPIKE-EXTRACTOR.

1,033,682.

Specification of Letters Patent. Patented July 23, 1912.

Application filed May 9, 1911. Serial No. 626,002.

To all whom it may concern:

Be it known that I, WILEY EDMONSON, a citizen of the United States, residing at Bicknell, in the county of Knox and State 5 of Indiana, have invented new and useful Improvements in Spike-Extractors, of which the following is a specification.

The invention relates to spike pullers, and more particularly to the class of devices for 10 extracting railroad spikes.

The primary object of the invention is the provision of a device in which a spike may be firmly clamped when holding a railway rail fastened to a tie, whereby the spike 15 may be quickly and easily extracted from the tie with the least possible leverage.

Another object of the invention is the provision of a device of this character in which a spike, when driven into a tie or 20 other base for the fastening of a rail or the like, may be fully extracted from the tie or other foundation in a single operation, without bending or otherwise damaging such spike.

25 A further object of the invention is the provision of a device of this character which is simple in construction, strong, durable, possessing few parts, efficient and reliable in operation, and inexpensive in manufacture.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a fragmentary perspective view of a cross tie, rail and spike, with the device in operative relation to said spike. Fig. 2 is a similar view, showing the spike extracted. Fig. 3 is a fragmentary top plan view of the device. Fig. 4 is a sectional view on the line 4—4 of Fig. 3. Fig. 5 is a perspective view of 45 the adjustable fulcrum member.

Similar reference characters indicate corresponding parts throughout the several views of the drawings.

Referring to the drawings by numerals, the 50 device comprises a lever or handle 5, preferably of the form shown, having a curvature 6 intermediate its ends to provide an angularly disposed lower extremity 7, the same being of rectangular shape in cross 55 section, and at the outer end thereof, on opposite sides of the same, are bolted or other-

wise secured yoke-like strap irons 8, in which are loosely engaged jaw members 9, each being formed with a medial outwardly bowed portion 10, while at one end is provided a chisel-edged terminal 11, and at its opposite end is formed an outturned angularly disposed extension 12, the loop-like strap irons 8 being adapted to traverse the medial bowed portion 10 of the jaws for the opening and closing thereof when disengaging the same from or engaging therewith the spike 13, as will be presently described. The angularly disposed extensions 12 obviate the necessity of pivoting the jaw members 9 and prevent the said jaw members from being pulled from the strap irons when the device is in use.

Formed on the lower ends of the jaw members 9 are upwardly curved laterally 75 extending nose projections 14, forming bearing seats 15 for a yoke ring or endless link 16 surrounding the jaw members 9 to hold the same against spreading apart too far when acted upon by the strap irons 8, on the raising or lowering of the lever or handle 5 during the operation of the device.

Slidably mounted upon the lower angular extremity 7 of the lever or handle is a guide yoke 17, carrying a fulcrum block 18, which, when adjusted longitudinally on the said extremity 7, is adapted to rest upon the ball of the rail 19, so that upon depressing the handle or lever 5, the jaw members 9 will be brought together, whereby the chisel-edges 11 will engage and bite into the spike 13, and on the continued downward pressure on the lever or handle 5, such spike will be pulled from the cross tie 20, in which the same is driven. However, should the spike be held fast, the fulcrum block 18 will be shifted, so that the guide yoke 17 thereof will be positioned in the bight or curvature 6, thereby enabling the free end of the fulcrum block 18 to contact with the web of the rail 19, so that on downward pressure upon the lever or handle 5, the spike 13 will respond to the pull exerted thereon for its extraction from the cross tie, as will be clearly obvious. It will be noted that the jaws will readily adjust themselves for clamping different sizes of spikes.

What is claimed is:

A spike extractor, comprising a lever having an angularly disposed end of squared formation in cross section, outwardly bent yoke-like straps fixed to opposite sides of

said angular end at the outer extremity thereof, a fulcrum arm adapted to lie beneath the said angular end and having a loop slidably engaging the said angular end, 5 outwardly bowed jaw members loosely engaged in said yoke-like straps, angular extensions formed on the said jaw members for preventing the disengagement thereof from the yoke-like straps when pulled upon, 10 laterally projecting upwardly curved noses

formed on the outer sides of the jaw members, and an endless loop surrounding the said jaw members and adapted to rest upon the said noses.

In testimony whereof I affix my signature in presence of two witnesses.

WILEY EDMONSON.
